Primary Examiner—James Gandy*Assistant Examiner*—Linda Brooks*Attorney, Agent, or Firm*—Herbert Dubno[57] CLAIM

The ornamental design for a chest of drawers, as shown and described.

DESCRIPTION

FIG. 1 is a top, front, left-side perspective view of the chest of drawers showing my new design, the back and bottom both being flat and unornamented;

FIG. 2 is a front elevational view thereof; and,

FIG. 3 is a right side elevational view thereof, the left side being a mirror image thereof.
